US00D832785S

(12) **United States Design Patent** (10) **Patent No.:** **US D832,785 S**
Rostami (45) **Date of Patent:** **** Nov. 6, 2018**

(54) **PORTABLE POWER SUPPLY**

- (71) Applicant: **Advanced Wireless Innovations LLC**,
Santa Monica, CA (US)
- (72) Inventor: **Ramin Rostami**, Calabasas, CA (US)
- (73) Assignee: **Advanced Wireless Innovations, LLC**,
Santa Monica, CA (US)

(**) Term: **15 Years**(21) Appl. No.: **29/589,974**(22) Filed: **Jan. 5, 2017**(51) LOC (11) Cl. **13-02**

Primary Examiner — Rosemary K Tarcza*Assistant Examiner* — Christy M Nemeth(74) *Attorney, Agent, or Firm* — Mintz Levin Cohn Ferris Glovsky and Popeo, P.C.(57) **CLAIM**

The ornamental design for a portable power supply, as shown and described.

DESCRIPTION

FIG. 1 is a perspective view of a portable power supply of my new design;

FIG. 2 is a side view thereof;

FIG. 3 is a rear view thereof; and,

FIG. 4 is a top view thereof.

The broken lines in the drawings are for the purpose of illustrating portions of the portable power supply that form no part of the claimed design.
